(57) **CLAIM**

An ornamental design for a connecting clip, as shown and described.

DESCRIPTION

FIG. 1 is a top, right side and front perspective view showing our new design;

FIG. 2 is a top plan view thereof;

FIG. 3 is a front view thereof;

FIG. 4 is a rear view thereof;

FIG. 5 is a left side view thereof; and,

FIG. 6 is a bottom plan view thereof.

In the drawings, the broken lines depict environmental subject matter only and form no part of the claimed design.
